C. N. GRAY.
APPARATUS FOR CARBURETING AIR.
APPLICATION FILED MAR. 4, 1916.

1,239,098.

Patented Sept. 4, 1917

UNITED STATES PATENT OFFICE.

CHARLES N. GRAY, OF YANKTON, SOUTH DAKOTA.

APPARATUS FOR CARBURETING AIR.

1,239,098.

Specification of Letters Patent. Patented Sept. 4, 1917.

Application filed March 4, 1916. Serial No. 82,051.

To all whom it may concern:

Be it known that I, CHARLES N. GRAY, a citizen of the United States, residing at Yankton, in the county of Yankton and 5 State of South Dakota, have invented a new and useful Improvement in Apparatus for Carbureting Air, of which the following is a specification.

An object of this invention is the production of apparatus for carbureting air and more particularly relates to means for evaporating oil or other hydrocarbon in a highly efficient and effective manner to furnish a highly combustible constituent in the 10 form of mixed air and liquid in a volatilized form for heating, illuminating, power and other purposes.

Further objects are to decrease the hazard of explosion by regulating the flow of gasoline or other liquid hydrocarbon into the carbureter and causing the parts of the apparatus to deliver a constant supply of rich mixture evenly, to enable the isolation of the supply tank containing the oil and the carbureting apparatus a long distance from the dwelling or structure where the mixture is used and to effectively pump the gasoline at such distance.

To these ends my invention comprises the 20 features of construction and combination of parts, which will be hereinafter more particularly described and pointed out in the claim.

In the accompanying drawing forming 25 part of this specification, Figure 1 is a side elevation of my improved apparatus for carbureting air; Fig. 2 is a plan of my improved carbureter forming part of said apparatus, a portion of said carbureter being 30 broken away to more clearly disclose the interior construction; Fig. 3 is a section taken upon the line X—X of Fig. 2; Fig. 4 is a section of a detail of my improved pump 35 employed in said apparatus, and Fig. 5 is a section of a detail of one of the pipes leading to the carbureter.

In the drawing, A is the usual air blower, which is operated by the usual weight motor B (not shown), situated near where the mixture developed by my improved apparatus 40 is to be used. C is a pump, the piston 2 in the cylinder 3 of which is reciprocated by the use of the weight motor B during its operation. D indicates the main gasoline or 45 other hydrocarbon supply tank which is filled through the supply pipe 4. Situated

near and above the supply tank is a carbureter F, which is supplied with air from the blower A through the air supply pipe 5. The lower end of the cylinder 3 of the force 50 pump C is connected with the carbureter F by a gasoline supply pipe 6, a branch 7 leading from the main gasoline supply tank D being connected with said pipe, so that when the piston 2 is being raised, gasoline flows 55 from the supply tank D into chamber G and is ultimately forced upwardly into the top of the carbureter by the downward stroke of piston 2. A small reservoir chamber G is interposed in the pipe 6 immediately below the junction of the branch 7 into which the gasoline flows, thereby maintaining a supply of gasoline for the air from the downward stroke of piston 2 to discharge 60 into the carbureter. A check valve 8 is interposed in the branch 7, so that gasoline or air cannot be forced through the branch into the supply tank D. During the upward suction stroke of the piston 2, air in pipe 6 is drawn back. By this means gasoline in 65 tank D runs freely through check valve 8 until it has filled chamber G and pipe 6 up to the level of gasoline in tank D. An auxiliary check valve 9 keeps the pump 70 from drawing gasoline up thereinto. Another check valve 11 interposed in the pipe 6 below the reservoir G locks and prevents the return of gasoline or mixture from the carbureter into the reservoir. The supply 75 tank D, carbureter F and reservoir G with 80 said connected piping is preferably embedded in the ground at a distance from the blower and pump, so as to reduce the hazard 85 from explosion or accident.

My improved carbureter is in the form of 90 a casing 15 having a plurality of partition walls 16 projecting alternately inwardly from the end walls 17 and 18 of said casing, thereby forming a channel running longitudinally of the casing backwardly and forwardly. The walls are evenly spaced apart and from the side walls of the casing, thereby forming a channel H of even width throughout its length. Hung from the top 95 19 of the casing at frequent intervals 100 throughout the length of said channel are a number of flexible baffle walls 20 made out of absorbent material, such as cheese cloth, which depend into the gasoline which is fed into the channel formed by the weirs 105 110 and casing. The gasoline in the carbureter is maintained at even height, an overflow

duct 21 being connected with the channel a short distance above the floor of the casing and emptying into the supply pipe 4 from whence it returns into the supply tank D. 5 The lower ends of the baffles 20 dip into the gasoline in the carbureter and by capillary attraction become thoroughly moistened. The air pipe 5 from the blower enters the carbureter through the top 19 at one end of 10 the channel containing the gasoline and passes backwardly and forwardly over the gasoline and below the baffles to the outlet end of the channel from whence the vapor emerges through the gas supply pipe 22 leading 15 to the locations where the mixture is to be employed for service. The lower ends of the baffle walls 20 are formed with upwardly projecting openings 23 in that portion of the baffle which dips into and extends slightly above the surface of the gasoline. These slits or openings in the baffle walls allow the passage of air and the air or vapor keeps the baffles in constant motion, thereby causing more thorough vaporization 25 of the gasoline and mixture of the air with the gasoline. By the use of these flexible flapping baffle walls which are hung by their upper ends from the top of the casing and constructed as described, more perfect carbureting action occurs. As many baffle walls may be used as desired, it being obvious that the more baffle walls employed, the greater the vaporization of the gasoline. 30 During the operation of my improved apparatus, gasoline is forced by the pump from reservoir chamber G into the top of the carbureter at that end of the channel in which air is forced by the blower. 35 A steady supply of rich mixture from the carbureter is produced, the reciprocations of 40

the piston in the pump being thoroughly equalized, so that there is substantially no unevenness in pressure of the mixture conducted from the carbureter through the supply pipes 22. During this operation chamber G acts as a seal to prevent air from forcing through into carbureter F with each stroke of the piston in the pump. The pump C has its piston 2 provided with oil grooves 25, which are adapted to be filled 45 with heavy oil through a channel 26 and branches 27 leading therefrom. 50

In accordance with the patent statutes, I have described the principles of operation of my invention, together with the apparatus which I now consider to represent the best embodiment thereof, but I desire to have it understood that the construction shown is only illustrative, and that the invention can be carried out by other means 55 and applied to uses other than those above set forth within the scope of the following claim. 60

Having described my invention, what I claim as new and desire to protect by Letters Patent is: 65

A carbureter comprising a closed tank having a gasoline feed and an air inlet, a gas outlet, and a plurality of spaced absorbent flexible baffle sheets attached along their upper edges to the top of the tank and loosely disposed transversely of the flow of gasoline and air, each of said sheets being provided with a V-slot centrally thereof, 70 said slot extending from the lower edge of 75 the sheet to a point approximately midway of its vertical length.

In testimony whereof, I have signed my name to this specification.

CHARLES N. GRAY.
